UNITED STATES PATENT OFFICE

ALEX BADMA, OF BUFFALO, NEW YORK

RADIO RECEIVING SYSTEM

Application filed January 23, 1931. Serial No. 510,816.

This invention relates generally to improvements in electron discharge apparatus and especially to improvements in the control means for such apparatus as used in the present types of radio receiving circuits.

In the operation of the present type of radio receiving apparatus utilizing "heater" valves it is generally accepted that upon energizing the apparatus for operation, a certain 10 interval, approximately a minute, is required to elapse before the apparatus is fully operative. The time thus expended is, of course, taken up to properly heat the cathodes of the valves to the proper electron emitting temperature by their respective filaments. To the 15 general radio public however, this has been a source of annoyance and has resulted in undesirable premature operation of the receiving set.

It is an object of the present invention to 20 reduce this interval to a minimum by providing a simple apparatus insertable in numerous receiving circuits which will not materially affect the operation of the circuits 25 therein or the present type of standard equipment used. This has been accomplished by applying an abnormal voltage to the filaments of the valves when energizing the set, causing a sudden rise of temperature of the same 30 with the accompanying heating of the cathodes and resulting energization of the output circuit. The output circuit thus rendered operative in turn through energizing a suitable device such as a relay immediately 35 acts and sets the filament voltage to normal value. The entire operation has been found to consume but three or less seconds of time as compared to the fifty to sixty seconds in previous types of apparatus.

Upon deenergization of the receiving apparatus the filament heating circuit is immediately changed by operation of the relay from a circuit operating at normal voltage to one operating at an abnormal voltage and 45 the apparatus is thus prepared for its rapid heating function for the next instance of its use. As the operation of this improvement is entirely automatic, it does not add to the number of the present manual controls of the 50 usual receiving set and therefore does not

affect the simplicity of operation of the same.

In the drawing, the figure is a diagram showing a multi-stage amplifier wherein is incorporated the filament control unit of the present invention.

The drawing shows a portion of a usual form of a multi-stage receiver incorporating the use of the well known "heater" type of audion valves 1. The anode or plate 2 of each of the valves is connected to the lead 3 of the primary of its transformer 4. The opposite leads 5 of the primary 6 of all the transformers are connected to each other by the wire 7 which in turn is connected to the wire 8. The wire 8 is connected to the positive side of the source of "B" current through a relay device hereinafter more fully described. The leads 9 of the secondaries 10 of the transformers are connected to the grids 11 of their respective valves, while the leads 12 of the secondaries are connected to the cathodes 13 of the same and to each other. The negative side of the "B" potential is connected to the cathodes by the wire 14. The leads 15 of the filaments of the tubes are connected to each other by the wire 14 and the leads 16 of the same are similarly connected by the wire 17. The structure set forth in the preceding description will be recognized by those skilled in the art as an operative form of a usual "hook-up" using the heater type valves and is utilized as an exemplary form as a basis for disclosing the principle of the invention as hereinafter described.

The above mentioned wire 8 is connected to the coil lead 18 of an electro-magnetic device 19. This device is preferably a suitable type of relay having a polarized core 20'. The opposite coil lead 18' thereof is connected to the positive source of plate potential. A bridging condenser 23 is connected between the leads 18 and 24 of the relay. The switch arm 20 of the relay is pivoted at 21 and is connected through the wire 22 to the wire 17 which connects the leads 15 of the filaments. Upon energization of the plate circuit the switch arm will be attracted to the core of the relay and upon deenergization of the plate circuit the switch arm under assistance of the

spring 25 will be positively moved outwardly from the relay.

When the switch arm is against the core 20' it is maintained on a switch contact 26 5 and when in the latter position it is maintained against the switch contact 27. A transformer 28 is provided to supply the filament potential and has a primary suitably connected to a source of alternating current 10 potential and a secondary 29 capable of approximately a ten volt output. The end lead 30 of the secondary is connected directly to the wire 14 and the other end lead 31 is connected to the contact 27 by the wire 32. The 15 secondary is tapped with a lead 33 at approximately the two and one half volt output portion thereof and is connected to the contact 26 by the wire 34.

In operation when the receiver is deener- 20 gized the filaments will be connected to receive the full ten volt output of the transformer secondary 29 as the switch arm 20 through its contact with the switch contact 27 maintains this circuit. Upon energization 25 of the receiver the filaments immediately receive a ten volt load and since the proper operating load of the same is two and one half volts, a rapid heating of the filaments will result with the accompanying heating 30 of their cathodes. This will cause an immediate electron bombardment of the plate from the cathode resulting in the energization of the plate circuit in the well known manner. Coincident with such plate circuit 35 energization the coil of the relay will be energized to pull the switch arm 20 against the core 20' thereof and to contact the switch arm with the switch contact 26 thus disengaging the switch arm from the ten volt contact 40 27 and connecting the filaments with the two and one half volt lead of the transformer for normal operation of the receiver. It has been found that the above described device permits the full operation of the receiver 45 within approximately three seconds of the application of power thereto. It has also been found that since the ten volt load on the filament through its control by the plate circuit is not permitted to cause excessive 50 heating thereof, that such loading does not materially affect the life of the filament.

It is not intended to limit the invention to the specific use of a relay for the purposes specified as it will be apparent to those skilled in the art that a number of electro- 55 magnetic devices may be substituted therefor to control the switch arm without departing from the spirit of the invention.

What is claimed is:

60 1. In a radio receiving system including an audion having a cathode and an anode coupled respectively to an input and an output circuit, a heater filament for heating the cathode thereof, a source of filament potential and a filament circuit connecting the

filament to its source of potential, the combination of a source of reduced filament potential, a switch operable to connect either of the sources of potential to the filament, and electro-magnetic means interposed in the 70 anode circuit and operative upon energization of the anode circuit to move said switch means to connect the source of reduced filament potential to the filament circuit, and said means when said anode circuit is de- 75 energized moving said switch means to connect the first named source of potential to the filament.

2. In a radio receiving system including an audion having a cathode and an anode 80 coupled respectively to an input and an output circuit, a heater filament for heating the cathode thereof, a source of filament potential, and a circuit connecting said source of potential to the filament, the combination of 85 means for varying the potential applied to said filament, operable to impress a relatively high voltage on said filament to quickly heat said filament to produce an electron flow from said anode, and to subsequently reduce 90 said voltage to maintain continued electron flow from said anode.

3. In a radio receiving system including an audion having a cathode and an anode coupled respectively to an input and an output circuit, a heater filament for heating the cathode, a source of filament potential, and a circuit connecting said source of potential to the filament, the combination of means for automatically varying the potential applied to said filament operable to impress a relatively high voltage on said filament to quickly heat said filament to produce an electron flow from said anode and to subsequently reduce 100 said voltage to maintain continued electron flow from said anode.

4. In a radio receiving system including an audion having a cathode and an anode coupled respectively to an input and an output circuit, a heater filament for heating the 110 cathode, a source of filament potential, and a circuit connecting said source of potential to the filament, the combination of control means for said source of potential, electro- 115 magnetic means interposed in the output circuit, said electromagnetic means being energized by the output circuit to operate said control means to first operate said filament at a relatively high potential and upon heating of the filament to an electron receiving tem- 120 perature to subsequently cause said filament to be operated at a lower potential.
